UNITED STATES PATENT OFFICE

CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE

SHEET METAL CONTAINER

Application filed May 16, 1931. Serial No. 537,885.

This invention relates broadly to sheet metal containers, and more specifically to a can or drum having a removable head or cover.

5 One object of the invention is to provide, in association with a can or drum body having a head or cover removably mounted in seated closing relation thereto, a device which constitutes both a clamp for securing said 10 cover in place and a hinge whereon said cover may be swung to and from open position.

A further object is to provide a can or drum structure of the character mentioned 15 embodying manually operable means whereby its cover may be drawn into closely seated closing relation to its body and also whereby said cover may be thrust to an elevated unseated position permitting convenient movement thereof to a fully open position.

A still further object is to provide a drum structure wherein the manually operable cover-clamping and elevating means above referred to also forms a hinge connection 25 between the cover and the drum body whereon said cover may be swung to and from its closing position and by means of which said cover is supported when in open position.

In describing the invention in detail, reference is herein had to the accompanying drawing, in which—

30 Figure 1 is a plan view of a fragmentary portion of the end of a can or drum embodying my invention;

Figure 2 is a fragmentary view of the same in side elevation;

Figure 3 is a detail section on line 3—3, Fig. 2, showing the cover occupying its seated position; and

40 Figure 4 is a similar section, showing the cover in its completely open position.

Referring to said drawing, 1 designates the body of a sheet metal container of cylindrical can or drum type, having an outwardly turned rim roll 2; and 3 indicates a head or cover for seating within the end of said body, said cover having an annular upwardly and outward curled flange 4 adapted to occupy closely seated overlying relation to 45 said rim roll.

Rigidly mounted upon the cover 3 adjacent to and inward of its flange 4 is the plate-like base 5 of one member of a hinge-like connection provided between said cover and the container body 1. Arcuately curved parallel arms 6, preferably formed integral with said base 5, extend in an upwardly and outwardly inclined direction from opposite ends of said base and have provided therein correspondingly curved and inclined slots 7 of suitable length. Shiftable in said slots are the opposite ends of a pivot pin 8 carried by the adjacent ends of a pair of arms 9 formed on a shiftable clamp 10 which constitutes a second member of said hinge-like connection. 55

Said clamp 10 comprises a sheet metal body having its upper end arcuately curved to form a saddle 11 adapted to seat in overlying relation to the cover flange 4. Said arms 9, located at opposite ends of said saddle 11, 60 are formed integral with and occupy positions at substantially right angles to the latter, as shown. The lower end of the clamp body has its opposite lateral edges turned inwardly to form parallel flanges 12 which are prolonged below the end of said body to form oppositely disposed lugs 13. Said lugs are mounted upon the opposite ends of a horizontally disposed pivot pin 14 carried by a manually shiftable lever 15 which normally occupies a pendent position in which it rests against or adjacent to a side of the container body 1. 65

Said lever 15 is pivotally mounted at its upper end upon a pivot pin 16 carried by outstanding lugs or arms 17 formed on a bracket plate 18 which is rigidly attached, as by spot-welds 19, to said container body directly below the rim roll 2 of the latter. 70

In practice, when the cover 3 has been applied in overlying loosely seated relation to the container body, the lever 15 occupies an outwardly-swung position wherein the thereto-pivoted clamp 10 has the saddle 11 thereof lightly resting upon the cover flange 4. Said cover is then forcibly drawn into firmly seated position wherein its said flange rests closely upon the rim roll of the container body, or upon an interposed gasket when such is employed, force being applied 75 80 85 90 95 100

to said lever for swinging the latter downwardly and inwardly to its substantially vertical position wherein the pivot pins 14 and 16 are vertically aligned beneath said rim roll. 5
 5 When the cover is to be removed, the lever 15 is forcibly swung outwardly to a substantially horizontal position wherein it not only elevates the saddle of the clamp 10 from its seated position relative to the cover flange 10 4, but also, through the arm 9 of said saddle and the therewith interengaged arms 6 of the rigidly mounted plate 5, effects elevation of the adjacent side of the cover 3 relative to the container body, whereupon said cover 15 and the clamp 10 may together be swung back to occupy the substantially horizontal positions shown in Fig. 4 of the drawings wherein they are supported through the seating of the lower end of the clamp body upon a 20 transverse upwardly-facing shoulder 20 formed on said lever 15.

As herein shown for illustrative purposes, said lever 15 is formed of a single piece of sheet metal shaped to form a substantially flat back 15a having its opposite lateral edges turned at right angles thereto to form flanges 22 which are extended or prolonged to form parallel arms 21 in which the opposite ends of the pivot pins 14 and 16 are engaged. 25

30 It will be understood that the connection between the container body and the cover, as hereinbefore described, constitutes a hinge whereon said cover may be swung either to closing position relative to an end of said body or to a supported out-of-the-way position relative to said end, and also constitutes a device whereby said cover may both be forcibly drawn into and elevated from firmly seated closing relation to said end of the 35 body. 40

What is claimed is—

1. The combination with a sheet metal container body having a rim, and a cover for said container body, said cover having a 45 flange for occupying seating relation to said rim, of a hinge member rigidly mounted on said cover entirely within said flange, a second hinge member pivotally connected to and complementing the first mentioned hinge member, said second member including a saddle for seating upon said cover flange, and a lever having a pivotal mounting on the container body beneath said rim, said second hinge member being pivotally mounted on said lever and being shiftable to and from saddle-seating position with movements of said lever. 50 55

2. The combination with a sheet metal container body having a rim, and a cover for said container body, said cover having a flange for occupying seating relation to said 60 rim, of a hinge member rigidly mounted on said cover, a second hinge member pivotally connected to and complementing the first mentioned hinge member, said first and

second hinge members having a lost motion connection therebetween said second member including a saddle, and a lever pivotally attached to said container body beneath the rim, said second hinge member being pivoted on said lever and being shiftable with movements of the latter to overlying pressure-applying relation to said cover flange for seating said cover in closing relation to the container body and to a cover-elevating position. 70 75

3. The combination with a sheet metal container body having a rim, and a cover for said container body, said cover having a flange for occupying seating relation to said rim, of a hinge member rigidly mounted on said cover, a second hinge member pivotally connected to and complementing the first mentioned hinge member, said second member including a saddle, and a lever pivotally attached to said container body beneath the rim, said second hinge member being pivoted on said lever and being shiftable with movements of the latter to overlying pressure-applying relation to said cover flange for seating said cover in closing relation to the container body and to elevated cover-releasing position, said second hinge member and said cover body being bodily shiftable on said lever to an outwardly swung position relative to said 80 85 90 95 container body.

4. The combination with a sheet metal container body having a rim, and a cover for said container body, said cover having a flange for occupying seating relation to said rim, of a hinge member rigidly mounted on said cover, a second hinge member pivotally connected to and complementing the first mentioned hinge member, said second member including a saddle, and a lever pivotally attached to said container body beneath the rim, said second hinge member being pivoted on said lever and being shiftable with movements of the latter to overlying pressure-applying relation to said cover flange for seating said cover in closing relation to the container body and to elevated cover-releasing position, said second hinge member and said cover being shiftable on the pivotal connection between said member and said lever to an outwardly swung position wherein they are supported by said lever. 100 105 110 115

5. The combination with a sheet metal container body having a rim, and a cover for said container body, said cover having a flange for occupying seating relation to said rim, of a hinge member rigidly mounted on said cover, a second hinge member pivotally connected to and complementing the first mentioned hinge member, said second member including a saddle, and a lever pivotally attached to said container body beneath the rim, said second hinge member being pivoted on said lever and being shiftable with movements of the latter to overlying pressure-applying re- 120 125 130

lation to said cover flange for seating said cover in closing relation to the container body and to elevated cover-releasing position, said second hinge member being shiftable to an outwardly swung position wherein it seats relative to said lever for supporting said cover in an approximately horizontal position.

6. The combination with a sheet metal container body having a rim, and a cover for said container body, said cover having a flange for occupying seating relation to said rim, of a hinge member rigidly mounted on said cover, a second hinge member pivotally connected to and complementing the first mentioned hinge member, said second member including a saddle for seating upon said cover flange, and a lever pivotally attached at one end to said container body beneath the rim, said second hinge member being pivoted to said lever intermediate the ends of the latter and being bodily shiftable with the latter to and from overlying pressure-applying relation to said cover flange for forcibly seating and unseating the cover with respect to said container body, said lever having a shoulder formed thereon, and said second hinge member and said cover being bodily shiftable to an outwardly swung position relative to said container body wherein said member seats upon said shoulder for supporting said cover.

7. In combination, a container, a cover

therefor, a hinge member on said cover, a lever pivotally connected to the container, a cover clamp pivotally connected to said lever and said member, and a stop on said lever for engaging said clamp when the cover is removed from the container.

8. In combination, a container, a cover therefor, a hinge member on said cover having a slot therein, a lever pivotally connected to the container, a cover clamp pivotally connected to said lever and said member, and a projection carried by said clamp and extendable into and shiftable along said slot.

9. In combination, a container, a cover therefor, a hinge member on said cover having a slot therein, a lever pivotally connected to the container, a cover clamp pivotally connected to said lever and said member, and a projection carried by said clamp and extendable into and shiftable along said slot, said lever having a stop thereon for engaging the clamp when said projection is shifted in the slot.

10. In combination, a container, a cover therefor, a clamping connection for clamping said cover in position on the container, a pivotal connection between the cover and the clamping connection, and inter-engaging stop means on said clamping connection for limiting movement of the cover relatively thereto when removed from the container.

In testimony whereof, I affix my signature.
CHARLES H. ROLLASON.
